US00D409137S

United States Patent [19]

Sumita et al.

[11] Patent Number: Des. 409,137

[45] Date of Patent: ** May 4, 1999

[54] RECHARGEABLE BATTERY

[75] Inventors: **Kaoru Sumita; Hidero Mitsui**, both of Tokyo, Japan

[73] Assignee: **Sony Corporation**, Tokyo, Japan

[**] Term: **14 Years**

[21] Appl. No.: **29/068,308**

[22] Filed: **Mar. 28, 1997**

[51] LOC (6) Cl. **13-02**

[52] U.S. Cl. **D13/103**

[58] Field of Search D13/103, 118, D13/119; 429/96-100, 163, 176

[57] CLAIM

The ornamental design for a rechargeable battery, as shown and described.

DESCRIPTION

FIG. 1 is a perspective view of a first embodiment of a rechargeable battery showing our new design;
FIG. 2 is a top plan view thereof;
FIG. 3 is a left side elevational view thereof;
FIG. 4 is a front elevational view thereof;
FIG. 5 is a bottom plan view thereof;
FIG. 6 is a right side elevational view thereof;
FIG. 7 is a rear elevational view thereof;
FIG. 8 is a perspective view of a second embodiment of a rechargeable battery showing our new design;
FIG. 9 is a top plan view of the embodiment of FIG. 8;
FIG. 10 is a left side elevational view of the embodiment of FIG. 8;
FIG. 11 is a front elevational view of the embodiment of FIG. 8;
FIG. 12 is a bottom plan view of the embodiment of FIG. 8;
FIG. 13 is a right side elevational view of the embodiment of FIG. 8; and,
FIG. 14 is a rear elevational view of the embodiment of FIG. 8.
